UNITED STATES PATENT OFFICE.

DANIEL R. PORTER, OF RANDOLPH, ASSIGNOR OF ONE-HALF TO JOHN A. WHIPPLE, OF BOSTON, MASSACHUSETTS.

WRENCH.

SPECIFICATION forming part of Letters Patent No. 278,265, dated May 22, 1883.

Application filed March 30, 1883. (No model.)

To all whom it may concern:

Be it known that I, DANIEL R. PORTER, of Randolph, county of Norfolk, and State of Massachusetts, have invented an Improvement in Wrenches, of which the following description, in connection with the accompanying drawings, is a specification, like letters on the drawings representing like parts.

My invention in wrenches has for its object 10 to simplify and cheapen the construction, and is shown embodied in a wrench in which one jaw, which may be called the "main" or "fixed" jaw, has the other jaw arranged to slide upon it and has the wrench-handle pivoted upon it, the said handle being adapted to both draw 15 the jaws together upon a nut or article to be turned and also to turn the wrench and nut grasped by it.

In my present invention the main or fixed 20 jaw has a shank portion of less thickness than the jaw itself, and the movable jaw also has a shank of less thickness, the said shanks being offset on opposite sides of the jaws, so that when the two jaws are in operative position 25 their shanks interlock or lie one upon the other. The movable shank is provided with a slot which receives a bolt passing through it and the shank of the fixed jaw, the said bolt thus holding the two jaws together in operative 30 position. The handle by which the jaws are closed together and the nut turned is pivoted upon the side of the shank of the fixed jaw, and thus readily engages the shank of the movable jaw.

35 Figure 1 is a side elevation of a wrench embodying this invention; Fig. 2, an edge view thereof, a portion only of the shank being shown; and Fig. 3, a side view of the movable jaw detached, showing the opposite side to 40 that shown in Fig. 1.

The main or fixed jaw *a* has a shank, *b*, of less thickness, lying at one side of the middle of the jaw, as best shown in Fig. 2, the said jaw *a* thus forming a shoulder, *2*, projecting 45 from the said shank *b*. The movable jaw *c* also has a thinner shank, *d*, it lying at the other side of the middle of the wrench and resting upon the shank *b* and against the said shoulder *2*. The jaw *c* itself thus also forms a 50 shoulder, *3*, (see Fig. 3,) which receives the

shank *b* of the jaw *a*, the said shanks *b* and *d* thus interlocking, as it were, with the jaws *a* and *c*. The shank *b* of the fixed jaw is provided with a bolt, *e*, preferably having a squared or flattened stem entering a slot, *4*, in the shank *d* of the movable jaw, the said bolt being provided with suitable heads, nuts, or projections to engage the faces of the said shanks, and thus hold the two jaws in the proper relative position. The jaw *c* thus has a sliding 60 movement toward and from the jaw *a*, it being guided in the said movement by the engagement of the shoulders *2* *3* with the corresponding shanks, and also by the bolt *e* in the slot *4*. The shank *d* of the movable jaw has a projection, *f*, embraced by the notch or forked end *g* of the handle *h*, pivoted on the shank *b* of the main jaw at 5.

When the wrench is in the position shown in Fig. 1, and the handle *h* moved in the direction of the arrow thereon, it will first turn on the pivot or stud *5* as a fulcrum, and in acting upon the projection *f* will move the jaw *c* in the direction of the arrow toward the jaw *a* until the said movement is stopped by the nut or other article to be turned placed between the said jaws, after which the further movement of the handle *h* will cause the entire wrench to rotate and turn the nut.

It will be seen that both the jaws can be 80 made as simple forgings, which will require scarcely any labor to finish and fit together, thus making a much cheaper wrench than when the shank of one jaw moves through an opening or passage in the body of the other 85 jaw, such opening or passage having to be made after the forging is formed by a very expensive operation.

I claim—

1. In a wrench, the combination of the main 90 jaw having a shank lying at one side of the middle of the wrench with the movable jaw having a shank lying at the other side of the middle of the wrench, each of the said jaws forming a shoulder to receive and guide the 95 shank of the other jaw, and the handle pivoted upon the side of the shank of the main jaw and operatively connected with the movable jaw, substantially as described.
2. The main jaw and its shank lying at one 100

side of the middle of the wrench, combined with the movable jaw having a slotted shank lying at the other side of the middle of the wrench, and the bolt upon the shank of the main jaw passing through the slot in the shank of the movable jaw, and the handle pivoted on the fixed jaw and operatively connected with the movable jaw, substantially as described.

3. The jaw *a*, with its shank *b*, and the jaw *c*, with its shank *d*, slotted and provided with a projection, *f*, the said jaws and their shanks

being interlocked, as described, combined with the bolt *e* and forked handle *h*, pivoted upon the shank *b* and engaging the projection *f*, all to operate substantially as described.

In testimony whereof I have signed my name to this specification in the presence of two subscribing witnesses.

DANIEL R. PORTER.
